UNITED STATES PATENT OFFICE.

RALPH SCOTT, OF WILKESBARRE, PENNSYLVANIA, ASSIGNOR OF ONE HALF TO MARCUS A. MILLER, OF NEW YORK, N. Y.

ELECTRIC-ARC LAMP.

SPECIFICATION forming part of Letters Patent No. 772,257, dated October 11, 1904.

Application filed October 14, 1903. Serial No. 177,013. (No model.)

To all whom it may concern:

Be it known that I, RALPH SCOTT, a citizen of the United States, residing at Wilkesbarre, in the county of Luzerne and State of Pennsylvania, have invented certain new and useful Improvements in Electric-Arc Lamps; and I do hereby declare the following to be a full, clear, and exact description of the invention, such as will enable others skilled in the art to which it appertains to make and use the same.

This invention relates to improvements in arc-lamps, and particularly to such as are adapted for use in direct-current circuits and adapted to be connected in multiple.

One object in view is the production of an arc-lamp capable of use on a circuit of constant voltage—say, for example, one hundred and ten—so that the lamp may be used on an ordinary incandescent-light circuit, a sufficient resistance being employed in the lamp to limit the current used by the lamp.

With these and further objects in view the invention comprises certain novel constructions, combinations, and arrangements of parts, as will be hereinafter fully described and claimed.

In the accompanying drawing the figure shows a vertical longitudinal central section through an arc-lamp embodying the features of the present invention.

Referring to the drawing by numerals, 1 indicates a suitable frame provided with means (not shown) for supporting a globe 2, inclosing the arc. The frame 1 may be of any preferred contour provided with any common form of support-engaging member 3, attached to the frame at its upper end. Within the frame, and preferably just beneath the support-engaging member 3, is positioned a vertically-arranged dash-pot 4, the plunger thereof (not illustrated) being the head of a carbon-tube 5, said carbon-tube in practice inclosing a carbon pencil 6, having its upper end connected with suitable means for maintaining perfect electrical contact with the tube 5, said contacting means not being illustrated. A soft-iron core or plunger 7 surrounds the tube 5 and is secured thereto by a set-screw 8, threaded through the plunger into contact with said tube. The plunger 7 may

be positioned at any desired point in the length of the tube 5 for securing the greatest efficiency from a given current, and said plunger is provided at its lower end with an annular flange 9, adapted to vary the reluctance of the path of the lines of force created by the electric magnet formed by said plunger and a cylinder hereinafter described. Said electromagnet consists, preferably, of a coil 10 of a single winding of coarse wire surrounding the plunger 7 or a portion thereof and inclosed by a cylinder 11, of soft iron. The upper end of the cylinder 11 is preferably provided with an inwardly-projecting annular shoulder 12, carrying a cylinder 13, of brass or other non-magnetic substance, said cylinder being of the length of cylinder 11 and extending down between the coil 10 and the plunger 7. The said upper end of the cylinder 11 is provided with laterally-projecting flanges 14. A bar of non-metallic material constituting a resistance is secured to and electrically connected with one of the flanges 14 and extends upwardly therefrom and at its upper end is provided with a conductor 16, connected in turn with a binding-post 17, which latter is insulated from the frame 1. The frame 1 is composed of conductive material and is connected by screws or other suitable attaching means 18, 18, connected to the cylinder 11, said attaching means forming supports for said cylinder and contacting parts, the cylinder 11 being thus grounded upon the frame 1—that is to say, said cylinder is electrically connected with said frame. A bar 19, of non-metallic material, similar to bar 15 and forming a resistance, rests upon and is insulated from the flange 14, the lower end of the bar 19 being connected electrically with one end of coil 10. The bar 19 extends upwardly from its support and is electrically connected at its upper end with a binding-post 19*, insulated from the frame 1 and carried thereby.

The lower end of frame 1 preferably carries a plate 20, upon which is mounted a guiding-spider 21, surrounding tube 5 and apertured to permit the passage of said tube, whereby the lower end of said tube is limited against lateral play. The lower end of said tube is

2
surrounded by a collar 22, which is fixed thereto and carries at one side a pivotally-connected link 23, said link depending from said collar and pivotally engaging at its lower 5 end a ring 24, surrounding carbon 6, whereby in operation upward movement of the tube 5 is adapted to bring the ring 24 to an inclined position for causing its edges to bite said carbon and lift the same with the tube, said ring 10 releasing the carbon upon being dropped into contact with the plate 20.

A depending bracket 25, of conductive material, is supported by plate 20 and is insulated therefrom, a suitable conductor 26 connecting 15 said bracket with the coil 10, said conductor extending, preferably, through an aperture formed in flange 9. The lower end of the bracket 25 is provided with any suitable engaging means for carrying a carbon pencil 27 20 below and in vertical alinement with the carbon 6.

The circuit of the present lamp may be traced as follows: Starting with binding-post 17, the current flows through conductor 16, resistance 25 15, flange 14, cylinder 11, frame 1, dash-pot 4, tube 5, carbon pencil 6, carbon pencil 27, bracket 25, conductor 26, coil 10, resistance 19, and to binding-post 19^a, binding-posts 19^a and 17 being connected to the line-wires.

30 In operation when a current is supplied to the lamp the flux from coil 10 will pick up plunger 7, thereby lifting tube 5 and through the operation of the clutch carried thereby lift carbon pencil 6 from contact with carbon 35 27, thus forming the arc. Should the current vary or the arc of the lamp become too long for any reason, the decrease in the flux will permit the plunger 7 to descend for compensating for such variation or for shortening the 40 arc, as necessary.

The cylinder 11 forms a path of very little reluctance, and the flange 9 decreases the air-gap and makes the parts extremely sensitive to variations in the current. Further, it will 45 be observed that the resistance-bars 15 and 19 are connected in series to offer double the resistance of a single bar and at the same time leave ample space within the frame 1 for the circulation of air for keeping the parts 50 cool, said frame being preferably provided with suitable apertures, as illustrated, for the free admission of air.

While I maintain that the construction and arrangement of the resistances 15 and 19 are 55 novel, I am presenting no claims in the present application for the resistance *per se*, for the reason that I have claimed the same in a companion application filed even-date here-with.

60 Having thus fully described my invention, what I claim as new, and desire to secure by Letters Patent, is—

1. In an arc-lamp, the combination of a coil, a core within the same, a movable carbon-support actuated by said core, a casing inclosing

said coil, a flange on said casing, a non-metallic resistance supported by said flange, a carbon-support beneath the first-mentioned support, and electrical connection between said coil and the last-mentioned support and between the first-mentioned support and said casing. 70

2. In an arc-lamp, the combination of a coil, a plunger within the same, a carbon-support actuated thereby, a cylinder inclosing said coil, 75 a flange projecting from the upper end of said cylinder, a pencil of resistance material supported by said flange and insulated therefrom, a carbon-support beneath the first-mentioned carbon-support, and electrical connections between said resistance and coil and between the coil and said last-mentioned support. 80

3. In an arc-lamp, the combination with a tube and a carbon-engaging clutch carried thereby, of a plunger surrounding said tube, 85 an annular flange carried by said plunger, a coil surrounding said plunger, a soft-iron casing surrounding said coil, a carbon-support beneath said tube, a resistance carried by and insulated from said casing, an electrical connection between the resistance insulated from 90 said casing and said coil, a similar connection between said coil and one of the carbon-supports, and electrical connections between the other of said carbon-supports and said casing. 95

4. In an arc-lamp, the combination with a frame, of a carbon-tube movably mounted therein, a plunger surrounding said tube, a flange carried by said plunger, a soft-iron cylinder surrounding said plunger and grounded 100 on said frame, a coil interposed between said cylinder and plunger, flanges on said cylinder, a resistance grounded on one of said flanges, a resistance carried by the flange and insulated therefrom, electrical connection between said 105 insulated resistance and said coil, a carbon-support beneath said tube, an electrical connection between said coil and said carbon-support, electrical connection between said carbon-tube and frame, line-wire binding-posts, 110 and electrical connections between said posts and said resistances.

5. In an arc-lamp, the combination with a tube, and a carbon-engaging clutch carried thereby, of a plunger surrounding said tube 115 and connected therewith, an annular flange carried by said plunger, a coil surrounding said plunger, a soft-iron casing surrounding said coil, a carbon-support beneath said tube, a resistance carried by said casing, electrical 120 connection between the resistance and said coil and one of the carbon-supports, and electrical connections between said tube and casing.

In testimony whereof I hereunto affix my signature in presence of two witnesses.

RALPH SCOTT
